United States Patent Office

Des. 181,588
Patented Dec. 3, 1957

181,588

COMBINED PLAYER CABINET AND FIGURINE

Byron Keith, Van Nuys, Calif.

Application October 18, 1956, Serial No. 43,408

Term of patent 14 years

(Cl. D56—1)

Fig. 1.

Fig. 2.

I claim:

The ornamental design for a combined player cabinet and figurine, as shown.
